(57) **ABSTRACT**

A pinch-preventing unit for bed guardrail includes a guardrail, a bed frame, and an actuating unit. The actuating unit is provided with a gap cover, which is located at a lower edge of the guardrail to close a gap existed between the lower edge of the guardrail and a top of the bed frame when the guardrail is in a lifted position for use, so as to ensure the safety use of the guardrail.

PINCH-PREVENTING UNIT FOR BED GUARDRAIL

FIELD OF THE INVENTION

The present invention relates to a pinch-preventing unit for bed guardrail, and more particularly to a bed guardrail unit being provided with a gap cover to close a gap existed between a bed frame and a lifted guardrail.

BACKGROUND OF THE INVENTION

To prevent a patient or a small child from unconsciously turning sideward and falling from a bed, guardrails have been designed and added to two lateral sides of the bed. In designing a bed guardrail, not only for a sickbed in a hospital or a stretcher on an ambulance, but also for a bed used in home, it is a must to ensure the guardrail is safe for a user. The guardrail for bed must satisfy a required safety coefficient, lest it should cause second injury or even death to a patient or child using the bed. That is, the guardrail for bed, particularly sickbed and stretcher, must be designed in consideration of the user's comfortableness, safety, and convenient operation.

However, the guardrail tends to form a hindrance to doctors and nurses in the process of emergent medical care and setting life support, or to the patient's family members in helping the patient in turning sideward, cleaning body, etc. Therefore, it has become an important issue to design a mechanism for smoothly and safely lifting or lowering the guardrail relative to a bed frame. For a guardrail to have sufficient space for smooth operation thereof, a quite large gap would frequently exist between the lifted guardrail and the bed frame. Such large gap tends to dangerously pinch the patient's or the small child's hand or neck, and needs improvement.

It is therefore tried by the inventor to develop a pinch-preventing unit for bed guardrail to effectively eliminate the drawbacks in the bed guardrail of prior art.

SUMMARY OF THE INVENTION

A primary object of the present invention is to provide a bed guardrail mechanism that enables reduced gap between a guardrail and a bed frame by adding a gap cover to the guardrail, so as to ensure the safety of a user of the guardrail.

Another object of the present invention is to provide a simple and convenient bed guardrail elevating mechanism, so that a bed guardrail could be smoothly moved between a lowered position and a lifted position, and the guardrail at the lowered position has a lower edge located above a floor surface by a distance no less than 120 mm to prevent an operator's feet from being injured by the lowered guardrail, and the guardrail at the lifted position has a lower edge located above the top of the bed frame smaller than 60 mm to prevent a user's hand or neck from being dangerously pinched between the guardrail and the bed frame.

To achieve the above and other objects, a pinch-preventing unit for bed guardrail is provided by the present invention to include a guardrail, a gap cover, an actuating unit, and a bed frame.

The actuating unit includes an operating plate for locking and unlocking the actuating unit. The operating plate has a hooking portion. The actuating unit also includes a hook, which has an upper and a lower hooked end. When the hooking portion of the operating plate is hooked to the upper hooked end of the hook, and the lower hooked end of the hook is hooked to the bed frame, the actuating unit is in a locked state. On the other hand, when the operating plate is operated

2

to force the lower hooked end of the hook to separate from the bed frame, the actuating unit is unlocked and a pivotal arm of the actuating unit could be upward turned by 180 degrees to lift the guardrail connected to an upper end of the pivotal arm.

- 5 The gap cover is pivotally connected to an upper end of the actuating unit to close a gap existed between a lower edge of the lifted guardrail and the top of the bed frame, so that any gap between the guardrail and the bed frame is always limited to be smaller than 60 mm without the risk of pinching a user's hand or neck. When the actuating unit is operated to lower down the guardrail, the lower edge of the lowered guardrail is distant from the floor surface no less than 120 mm without the risk of colliding with the floor surface or an operator's feet.

15 BRIEF DESCRIPTION OF THE DRAWINGS

The structure and the technical means adopted by the present invention to achieve the above and other objects can be best understood by referring to the following detailed 20 description of the preferred embodiments and the accompanying drawings, wherein

FIG. 1 is an exploded perspective view of a pinch-preventing unit for bed guardrail according to a preferred embodiment of the present invention;

25 FIG. 2 is an assembled view of FIG. 1;

FIG. 3 is a perspective view showing the pinch-preventing unit for bed guardrail according to the preferred embodiment of the present invention in a lowered position;

FIG. 4 is a side view of FIG. 3;

30 FIG. 5 is a perspective view showing the pinch-preventing unit for bed guardrail according to the preferred embodiment of the present invention in a lifted position; and

FIG. 6 is a side view of FIG. 5.

35 DETAILED DESCRIPTION OF THE PREFERRED EMBODIMENTS

Please refer to FIG. 1 that is an exploded perspective view of a pinch-preventing unit for bed guardrail according to a 40 preferred embodiment of the present invention. As shown, the pinch-preventing unit for bed guardrail includes a guardrail 1, a gap cover 2, an actuating unit, and a bed frame 4.

The guardrail 1 is provided on an inner lower side facing toward the bed frame 4 with a recess 11.

45 The actuating unit 3 is provided at an upper end with an upper mounting bracket 31 for fixedly mounting to the recess 11 to thereby connect the guardrail 1 to the actuating unit 3, and at a lower end with a lower mounting bracket 33 having mounting holes 333 formed thereon. By aligning the mounting holes 333 with holes 41 correspondingly provided on the bed frame 4 and threading fastening elements through the aligned mounting holes 333 and holes 41, the guardrail 1 and the gap cover 2 connected to the actuating unit 3 may be movably attached to the bed frame 4.

50 55 The actuating unit 3 includes a pivotal arm 32, an upper and a lower end of which are respectively provided with a round bar 321, 322. The round bar 321 has a shaft hole 3211 axially extended a full length of the round bar 321. The pivotal arm 32 is pivotally connected at the upper end to the upper mounting bracket 31 via the round bar 321, and pivotally connected at the lower end to a lug 332 on the lower mounting bracket 33 via the round bar 322.

55 60 The actuating unit 3 also includes a locking mechanism 34, an upper and a lower end of which are pivotally connected to the upper and the lower mounting bracket 31, 33, respectively. The locking mechanism 34 includes an operating plate 341 having a hooking portion 3411, and a hook 342 provided

at upper and lower ends with a hooked end 3421 each. When the hook 342 is hooked at the upper hooked end 3421 to the hooking portion 3411 of the operating plate 34 and at the lower hooked end 3421 to a hook portion 334 on the lower mounting bracket 33, the locking mechanism 34 is in a locked state. By controlling the operating plate 341, the hooking portion 3411 thereof may be caused to force the upper hooked end 3421 of the hook 342 to move downward, so that the lower hooked end 3421 of the hook 342 is separated from the hook portion 334 on the lower mounting bracket 33 and accordingly, the bed frame 4. At this point, the locking mechanism 34 is in an unlocked state.

The gap cover 2 is provided on an inner side with at least one lug 21, on which a through hole 211 is formed. By extending an insertion pin 23 through the through hole 211 on the lug 21 of the gap cover 2 and two pin holes 343 correspondingly formed on the locking mechanism 34, the gap cover 2 may be connected to the locking mechanism 34.

Please refer to FIG. 2 that is an assembled view of FIG. 1. As can be clearly seen from FIG. 2, the gap cover 2 is located between a lower edge of the guardrail 1 and a top of the bed frame 4. With the gap cover 2, a gap between the lower edge of the guardrail 1 and the top of the bed frame 4 may be controlled to be less than 60 mm. Therefore, the risk of having an excessively large gap between the lower edge of the guardrail 1 and the bed frame 4 may be avoided.

Please refer to FIGS. 3 and 4 that are perspective and side views, respectively, showing the pinch-preventing unit for bed guardrail according to the preferred embodiment of the present invention is pivotally turned to a lowered position. In this position, the guardrail 1 and the gap cover 2 are located at a position lower than the top of the bed frame 4 with the gap cover 2 pivotally turned toward the inner lower side of the guardrail 1, so that a distance A no less than 120 mm is existed between the lower edge of the lowered guardrail 1 and a floor surface C to satisfy the requirement specified by related safety code. With the distance A, the guardrail 1 and the gap cover 2 during the operation thereof are prevented from colliding with the floor surface C to produce interference or colliding with an operator's feet to injure the operator.

Please refer to FIGS. 5 and 6 that are perspective and side views, respectively, showing the pinch-preventing unit for bed guardrail according to the preferred embodiment of the present invention is pivotally turned to a lifted position. To do this, first unlock the actuating unit 3, and the pivotal arm 32 is pivotally upward turned about the lug 332 on the lower mounting bracket 33 by 180 degrees until the pivotal arm 32 is moved to locate above the lug 332. At this point, the lower hooked end 3421 of the hook 342 in the locking mechanism 34 would hook to the lower mounting bracket 33, as shown in FIG. 1, so that the actuating unit 3 is locked and the guardrail 1 is lifted and held in place to locate above the lug 332, and a gap B between the lower edge of the lifted guardrail 1 and the top of the bed frame 4 is closed by the gap cover 2. It is noted there is a transverse gap D existed between a lower outer side of the lifted guardrail 1 and a lateral outer side of the bed frame 4. However, the gap cover 2 has a lower part 22 formed into a downward curved surface 221, which is extended from the lower edge of the guardrail 1 toward the top of the bed

frame 4 to also properly close the gap D between the lifted guardrail 1 and the bed frame 4 and thereby solve the problem of an excessively large gap D.

The present invention has been described with a preferred embodiment thereof and it is understood that many changes and modifications in the described embodiment can be carried out without departing from the scope and the spirit of the invention that is intended to be limited only by the appended claims.

10. What is claimed is:

1. A bed comprising
a frame,
a guardrail,

an actuating unit coupling the guardrail to the frame for movement between a raised position in which the guardrail is above the frame and a lowered position in which the guardrail is below the frame, the actuating unit having at least one arm that pivots relative to the guardrail and relative to the frame to guide the movement of the guardrail between the raised and lowered positions, and

a gap cover fastened to the actuating unit to pivot therewith as the guardrail is moved between the raised and lowered positions, the gap cover including end portions extending in opposite directions beyond the actuating unit, the gap cover being situated underneath the guardrail when the guardrail is in the raised position to substantially close a horizontally extending gap located between a lower edge of the guardrail and a top of the frame.

2. The bed of claim 1, wherein the end portions of the gap cover include curved portions that curve toward the frame when the guardrail is in the raised position.

3. The bed of claim 2, wherein the at least one arm of the actuating unit comprises a pair of spaced apart arms, a space is defined between the curved portions of the gap cover, and portions of each of the pair of spaced apart arms are received in the space when the guardrail is in the raised position.

4. The bed of claim 3, wherein the pair of spaced apart arms are situated outside the space when the guardrail is in the lowered position.

5. The bed of claim 1, wherein the actuating unit includes a locking unit and the gap cover is fastened to the locking unit.

6. The bed of claim 5, wherein the gap cover has at least one lug and the gap cover is fastened to the locking unit by a pin that extends through a first opening in the lug and a second opening in the locking unit.

7. The bed of claim 6, wherein the at least one lug of the gap cover comprises a pair of spaced apart lugs and a portion of the locking unit is situated between the pair of spaced apart lugs.

8. The bed of claim 7, wherein the at least one arm of the actuating unit comprises a pair of spaced apart arms and each lug of the pair of lugs is situated between the locking unit and a corresponding one of the pair of spaced apart arms.

9. The bed of claim 6, wherein the pin extends parallel with the axes about which the at least one arm pivots relative to the guardrail and the frame.
